AMALGAMATING MACHINE

Guy C. Anderson, San Francisco, Calif.

Application January 14, 1936, Serial No. 59,060

5 Claims. (Cl. 209—191)

This invention relates to improvements in amalgamating machines and more particularly to gold separators and the method of separating precious values from mineral pulp.

In the natural state gold particles are often found in close association with magnetite, iron magnetic oxides and non-ferrous magnetizable materials, especially in black sand. Fine gold may adhere to such materials, or the gold may be encased in films containing magnetizable constituents.

Among the objects of the invention is to effect mechanical separation of the gold from the magnetizable materials without removing such materials from the aggregated mass.

Another object is to facilitate the amalgamation of free gold and gold bearing particles in the presence of mercury.

Another object is to subject the amalgamating area to the influence of a magnetic field.

Another object is to subject gold bearing pulp to a rubbing action in the presence of mercury within a magnetic field.

A further object is to subject gold bearing pulp in the presence of mercury to vibratory oscillations of high frequency.

Other objects and advantages will appear as the description progresses.

In this specification and the accompanying drawings the invention is disclosed in its preferred form. However it is to be understood that it is not limited to this form because it may be embodied in other forms within the purview of the claims following the description.

In the two sheets of drawings:

Fig. 1 is a vertical section of an amalgamating mill constructed in accordance with this invention.

Fig. 2 is a plane detail of the rotor and stator faces.

Fig. 3 is a side elevation, partially in vertical section, of the magnetic amalgamating trap for use in combination with the amalgamating mill in the present process of magnetic-amalgamation.

Fig. 4 is a detail view in horizontal section of one of the baffles in the amalgamating trap.

In detail the construction illustrated in the drawings, referring first to Fig. 1, comprises the magnetic bowl 1, mounted upon the pedestal 2 or any suitable base. A series of mills may be

The vertical shaft 7 extends upward through this neck and is mounted in the radial thrust bearing 8 and the step bearing 9 supported within the pedestal. This shaft is driven by the bevel gear 10 and the gear 11 fixed on the counter-shaft 12, which is driven by the pulley 13 or any other suitable means.

The rotor 14 has the upstanding blind hub 15 clearing the neck 6 and is splined on the end of the shaft 7. The rotor clears the bottom of the bowl and has the upper flat tractive surface 16, provided with the depressions 17. The nature of this grinding or rubbing surface can be varied to suit the particular nature of the pulp being acted upon.

The stator 18 is similar to the rotor in general outline and has the surface 16' contacting therewith, and the center dome 19 enclosing the hub of the rotor.

The splash plate or cover 20 is bolted to the rim 3 and overhangs the stator. The manual stud screws 21 are fixed in the stator 18 and threaded through the hand wheels 21' above the cover to regulate the mechanical pressure against the pulp flowing between the rotor and stator.

The pulp introduced into the dome 19 through the hopper 22 is distributed by the rotating hub 15 of the rotor and passes between the rotor 14 and stator 18 before escaping through the overflow pipe 23 fixed through the rim 3 beneath the cover 20.

The inductive coil 24 of an electro-magnet is introduced between the flanges 4 and 5 and encircles the rim of the bowl in line with the rotor and stator. This coil is in circuit with the generator 25 and the switch 26. When the switch is closed the coil is energized and creates a magnetic field acting upon the magnetizable material passing through the mill and particularly while being rubbed between the rotor and stator.

Where first cost is a controlling factor the apparatus can be built of cast iron. But the iron tends to shield or concentrate the magnetic lines of force within the iron of the bowl. It is preferable therefore to form the bowl and other parts within the magnetic field of non-magnetic material. There are metal alloys and vitreous materials suitable for the purpose, which will permit the magnetic force to act directly upon the magnetic oxides and the like, in the flowing pulp.

From the overflow 23 the pulp is conducted to the lower end of the columnar trap 27 and overflows at 28. The

coil 29 in circuit with the generator 25 and the switch 30.

The trap 27 contains the mercury 31 in its lower portion with the amalgam draw off pipe 32 at its lowest point. To impede the flow of pulp, keep it turbulent and thoroughly mixed the series of baffle disks 32, interspaced on the rod 33, are inserted into the trap to force the pulp into more diffused contact with the mercury 31.

10 The same magnetic conditions are set up in the trap as exist in the bowl 1. The trap 27 is intended to amalgamate any gold values not taken up in the bowl.

15 The pulp being fed through the hopper 22 is mixed with mercury in a divided state and is rubbed into contact with the gold particles in passing between the rotor and stator 14-18. The mercury 34 accumulates in the bottom of the bowl 1, and is kept constantly agitated by 20 the rotor so that the surface of the mercury 34 is kept bright and lively to select any gold values issuing at the peripheral discharge from the rotor-stator 14-18, into the bowl. This rubbing action disintegrates any tarnish or film coatings 25 enveloping the gold or other values and renders them more readily amalgamatable. While there is a certain grinding action takes place between the rotor and stator due to the gritty nature of the pulp the particular function is to rub the gold 30 into the mercury and cause the mechanical separation of the precious values from the granular material of the pulp.

Much of this material is magnetic oxide and other magnetizable material polarized or magnetically activated in the magnetic field of the 35 bowl 1 and the trap 27. In this condition the adhesive force is broken or minimized and the amalgamatable values are immediately released and pass into the mercury.

40 The magnetic field also prevents amalgamation of ferrous and ferric compounds. This makes it possible by this process to recover precious values from ores and sands which have heretofore been impossible because of the sickening of the mercury due to the absorption of iron compounds associated with the values.

The vibratory oscillations set up within the mercury by the magnetic field, especially when 45 alternating current is used, tends to rupture the sickened skin which forms on the mercury, keeping the surface bright, clean and more attractive to the values present. Since this vibration extends throughout the whole mass of the flowing aggregate and the mercury, it increases the number of collisions between the gold particles and the mercury, thus speeding up amalgamation and conserving mercury. These effects are present in both the rubbing mill, Fig. 1, and the magnetic mercury trap, Fig. 3.

The field strength and arrangement of the coils 24 and 29 may be widely varied in the application of the invention to the different types of amalgamators required for various mineral conditions. A field of 2000 gauss will suffice for the 5 amalgamating bowl illustrated. A considerable reduction of this field strength will however not affect the efficacy of the amalgamation.

Having thus described this invention what is claimed and desired to be secured by Letters 10 Patent is:

1. A mill in the class described including a bowl; a pulp rubbing means in said bowl; an amalgamating substance in said bowl in contact with said rubbing means; an electro-magnetic coil surrounding said bowl; and means for passing 15 alternating current through said coil.

2. A mill in the class described including a bowl; a pulp rubbing means in said bowl; an amalgamating substance in said bowl in contact 20 with said rubbing means; a single electro-magnetic coil arranged to set up a field in said bowl; and means for passing alternating current through said coil.

3. A mill in the class described including a 25 bowl; a rotor in said bowl; means for driving said rotor; a stator in said bowl in operative relation to said rotor; means for adjusting said stator with respect to said rotor; means for introducing the pulp to be treated between said 30 rotor and said stator; an amalgamating substance in said bowl in contact with said rotor and stator; an electro-magnetic coil surrounding said bowl; and means for passing alternating current through said coil.

4. A mill in the class described including a bowl having an upwardly projecting neck; a rotor located below the level of said neck and having a hub extending above said neck; a shaft extending upwardly through said neck and engaging 40 said hub; means for rotating said shaft; a stator in said bowl in operative relation to said rotor and having a hopper extending upwardly therefrom; an amalgamating substance in said bowl in contact with said rotor and said stator; an electro-magnetic coil surrounding said bowl; and means for passing alternating current 45 through said coil.

5. A mill of the class described including a bowl; a rotor in said bowl having a flat tractive 50 surface with depressions therein; means for driving said rotor; a stator in said bowl having a flat surface with depressions therein in operative relation with the flat surface of said rotor; an amalgamating substance in said bowl in contact 55 with said rotor and stator; an electro-magnetic coil surrounding said bowl; and means for passing alternating current through said coil.
